PORTABLE TOILET CABANA

David B. Harding, Grosse Pointe Woods, Mich., assignor to Sani-Jon of America, Inc., Warren, Mich.

Filed Apr. 3, 1967, Ser. No. 6,489

Term of patent 14 years

(Cl. D13—1)

FIG.1

FIG. 1 is a front elevational view of a portable toilet cabana, showing my new design.

FIG. 2 is a right side elevational view thereof, the left side being a substantially identical mirror image.

FIG. 3 is a rear elevational view thereof.

FIG. 4 is a top plan view thereof.

I claim:

The ornamental design for a portable toilet cabana, as shown and described.
